US00D723863S

(12) **United States Design Patent**
Arnold et al.

(10) **Patent No.:** **US D723,863 S**
(b4) **Date of Patent:** **** Mar. 10, 2015**

(54) **MUG LID**

(71) Applicants: **Kent M. Arnold**, Cincinnati, OH (US);
Troy Cooksey, Cincinnati, OH (US);
Bradley M. Ruff, Bowling Green, OH (US)

(72) Inventors: **Kent M. Arnold**, Cincinnati, OH (US);
Troy Cooksey, Cincinnati, OH (US);
Bradley M. Ruff, Bowling Green, OH (US)

(73) Assignee: **Broodle Brands, LLC**, Cincinnati, OH (US)

(**) Term: **14 Years**

(21) Appl. No.: **29/464,590**

(22) Filed: **Aug. 19, 2013**

Related U.S. Application Data

(62) Division of application No. 29/412,988, filed on Feb. 9, 2012, now Pat. No. Des. 688,092.

(51) **LOC (10) Cl.** **07-02**

(52) **U.S. Cl.**

USPC **D7/392; D9/449**

(57) **CLAIM**

We claim the ornamental design for a mug lid, as shown and described.

DESCRIPTION

FIG. 1 is a perspective view of the mug lid;

FIG. 2 is a right side elevation thereof;

FIG. 3 is a front elevation view thereof;

FIG. 4 is a left side elevation view thereof;

FIG. 5 is a back elevation view thereof;

FIG. 6 is a top view thereof; and,

FIG. 7 is a bottom view thereof.

The broken line showing of a portion of the mug lid illustrates a portion of the mug lid which forms no part of the claimed design. The broken line showing of the mug illustrates environmental structure and forms no part of the claimed design.

1 Claim, 7 Drawing Sheets
